UNITED STATES PATENT OFFICE.

NOAH CARTIER, OF BIDDEFORD, MAINE, ASSIGNOR TO JACOB CARTIER AND ARTHUR GEORGE PELLETIER, OF SAME PLACE.

WARP-THREAD AND SELVAGE GUIDE FOR LOOMS.

SPECIFICATION forming part of Letters Patent No. 658,341, dated September 25, 1900.

Application filed June 28, 1899. Serial No. 722,205. (No model.)

To all whom it may concern:

Be it known that I, NOAH CARTIER, a citizen of the United States, residing at Biddeford, in the county of York and State of Maine, have invented a Warp-Thread and Selvage Guide for Looms, of which the following is a specification.

In the operation of weaving the warp-threads, especially the selvage-threads on each side of the warp, frequently overlie each other and become intermixed, so that in the event of the breakage of one of these threads it is often difficult to find the broken ends in order to tie them together, much loss of time being thereby occasioned, resulting in pecuniary loss to the weaver who works by the "cut" or piece.

To overcome this difficulty is the object of my invention, which consists in a narrow plate or strip adapted to be so fastened to a loom as to extend into the path of the warp-threads and being provided with a series of holes forming guides for said threads, whereby they are separated from each other and held apart as they pass to the shuttle-race, the threads which are admitted to the guide-holes through slits extending therefrom to the edge of the strip, being thereby prevented from overlying each other and becoming intermixed, as hereinafter more fully set forth.

In the accompanying drawings, Figure 1 is a perspective view of my warp-thread guide and the adjacent portion of the loom-frame by which it is supported and from which it projects into the path of the warp-threads. Fig. 2 is an enlarged side elevation of my warp-thread guide and its holder, the position which it occupies when not required for use being indicated by dotted lines.

In the said drawings, A represents a portion of the framework of a loom; B, the warp-beam; C, the guide-roll, over which the warp-threads *a* pass to the shuttle-race, and *b* the "lease-rod."

D is a narrow plate or strip, preferably composed of sole-leather or leather-board, but which may be made of any other suitable material. Through a hole *c* at the outer end of this strip is looped a piece of spring-wire *d*, twisted at *e*, whereby the two portions are caused to bear with a yielding pressure

against the opposite sides of the strip D, thereby holding it in a horizontal position in the path of the warp-threads between the guide-roll C and the shuttle-race, as shown in Fig. 1, but permitting it to be swung down on the looped end of the wire as a pivot into the position shown in dotted lines in Fig. 2 when not required for use. The wire *d*, which forms a holder for the strip D, is bent at its outer end into the proper shape to fit around the adjacent portion A of the loom-frame, over which it is sprung, as shown in Fig. 1, and from which it can be easily removed when desired, the free end 10 being provided with a hook 12, which is caught over the adjacent portion 15, thereby forming a tight clasp. Any other suitable form of holder may, however, be employed which will properly support the strip D and hold it in position for use, the strip being preferably pivoted to the end of the holder, so that it can be swung down into a vertical position when not required for use. The strip D is provided with small holes *f*, spaced apart, each hole forming a guide for a single warp-thread, which passes therethrough. These holes are preferably arranged in two parallel rows, the holes of one row alternating with those of the other row, as shown; but, if desired, the strips may be made with a single row of holes only. Extending at an angle from the upper or lower edge of the strip D to one side of each hole *f* is a slit *g*, through which the warp-thread can be readily slipped into its hole, the inclination of said slit and its tangential arrangement with respect to the hole with which it communicates effectually preventing the warp-thread from slipping out of said hole after having been placed therein. At the point where each slit *g* reaches the edge of the strip D is formed a notch *h*, which forms a guide for locating the warp-thread in a position to instantly enter the slit *g*, thereby enabling the weaver to place the warp-threads in the proper holes in the shortest possible time. The arrangement of the holes *f* in two alternating rows, as shown, with their entrance-slits extending both to the top and bottom edge of the strip, enables me to place the holes much nearer together than would be practicable if the holes were placed

- in a single straight row with their slits extending to one edge only of the strip, as the slits must be sufficiently far apart to avoid undue weakening of the body of the guide-
 5 strip. By the employment of the above-de-
 scribed thread-guiding device it will be seen
 that the warp-threads which pass through
 the holes *f* are separated from each other
 and held apart as they pass from the roll *C* to
 10 the shuttle-race, whereby all liability of their
 riding one over the other and becoming in-
 termixed, as heretofore, is entirely avoided,
 and consequently the breakage of a thread
 15 will be readily noticed, enabling the broken
 ends to be easily found and united a great
 saving of time being thereby effected, and
 the production of the loom proportionately
 increased, to the great advantage of the
 20 weaver.
 20 In the drawings I have shown the thread-
 guide of such length as to receive the selvage-
 threads only, as these threads are most liable
 to be intermixed; but it will be obvious that
 25 the guide may be made of greater length, or,
 if desired, of such length as to extend en-
 tirely across the loom to receive the entire se-
 ries of warp-threads without departing from
 the spirit of my invention.
 30 I prefer to make my thread-guide of leather
 or leather-board on account of its softness
 and consequent freedom from liability to cut
 the threads as they pass through its holes;
 but it may be made of any other material that
 35 may be found adapted for the purpose.
 35 What I claim as my invention, and desire
 to secure by Letters Patent, is—
 1. A warp-thread guide consisting of a strip
 or plate provided with a series of holes for

the passage of the threads, whereby they are
 separated and held apart, and having inclined 40
 slits arranged tangentially with respect to
 said holes, and extending therefrom to the
 edge of the strip, for the admission of the
 threads to the holes, substantially as de-
 scribed.

2. A warp-thread guide consisting of a strip
 or plate provided with holes for the passage
 of the threads, and slits leading from its edge
 to said holes in combination with a support-
 ing device or holder adapted to be attached 50
 to the loom, said strip being pivoted to said
 holder, whereby it may be turned down into
 a vertical position when not required for use,
 substantially as described.

3. The combination with a warp-thread 55
 guide consisting of a strip or plate provided
 with holes for the passage of the threads, and
 slits leading from its edge to said holes, of a
 support or holder composed of spring-wire,
 and adapted to be sprung over and clasped 60
 around an adjacent portion of the frame of a
 loom, whereby it is held in the path of the
 warp-threads, substantially as described.

4. A warp-thread guide consisting of a strip
 or plate provided with two parallel rows or 65
 series of holes for guiding the threads, the
 holes of one row alternating with those of the
 other, and entrance-slits for the threads lead-
 ing from said holes to the upper and lower
 edges of the strip, substantially as described. 70

Witness my hand this 17th day of May,
 A. D. 1899.

NOAH CARTIER.

In presence of—
 EMILE A. FORTIN,
 MARIE MÉNARD.
